(57) CLAIM

The ornamental design for a microphone filter, as shown and described.

DESCRIPTION

FIG. 1 is a perspective view of a microphone filter showing my new design;

FIG. 2 is a front elevational view thereof;

FIG. 3 is a right side elevational view; the left side elevational view is a mirror image thereof;

FIG. 4 is a rear elevational view thereof;

FIG. 5 is a top side elevational view; and,

FIG. 6 is a bottom view thereof.

The broken line showing of a side firing microphone is for illustrative purposes only and forms no part of the claimed design.
